DESIGN FOR AN ELECTRIC WASHING MACHINE

Edward S. Preston, Hinsdale, Ill., assignor to Chicago Electric Manufacturing Company,
Chicago, Ill., a corporation of Illinois

Application September 11, 1939, Serial No. 87,139

Term of patent 7 years

To all whom it may concern:

Be it known that I, Edward S. Preston, a citizen of the United States, residing at Hinsdale, Du Page County, Illinois, whose post office address is 419 E. Fourth Street, Hinsdale, Illinois, have invented a new, original, and ornamental Design for an Electric Washing Machine, of which the following is a specification, reference being had to the accompanying drawings, forming a part thereof.

The dominant features of my design reside in the portions illustrated in solid lines.

I claim:

The ornamental design for an electric washing machine, substantially as shown and described.

EDWARD S. PRESTON.
